(57) **CLAIM**

The ornamental design for an apparatus for holding roof shingles, as shown and described.

DESCRIPTION

FIG. 1 is a top perspective view of an apparatus for holding roof shingles showing my new design;

FIG. 2 is a top plan view thereof;

FIG. 3 is a bottom plan view thereof;

FIG. 4 is a front elevation view thereof;

FIG. 5 is a rear elevation view thereof; and,

FIG. 6 is a left side elevation view thereof, the right side view being a mirror image of that shown.
